METHOD OF REFRIGERATION

Louis P. Reiss, Dallas, Tex.

Application August 14, 1931, Serial No. 557,026

3 Claims. (Cl. 62—91.5)

This invention relates to improvements in refrigeration, either industrial or domestic, and it has particular reference to a method or process by which to prolong the state of change of water 5 ice when used as a refrigerant.

The principal object of the invention resides in a method of combining water ice and solid carbon dioxide to lower the temperature in a given area and maintain the temperature uniformly over a long period. The action of the water ice in passing from a solid to a liquid is prolonged for an indefinite period of time, so long as solid carbon dioxide is added.

The invention comprehends the provision of a new and useful method by which to improve the refrigeration of railway cars. Particularly in railway fruit and vegetable cars it is necessary to maintain a set temperature at all times, when loaded, which necessitates the stopping of the 10 train at intervals to have additional ice placed in the bunkers of the cars. This is an expensive procedure as the equipment is lying idle, train crews are idle and the running time is reduced. The invention affords a method by which to associate water ice with solid carbon dioxide, both 15 refrigerants being placed in the bunkers of the refrigerator cars, and will furnish satisfactory refrigeration for longer periods and will therefore permit greater distances to be travelled 20 before re-icing becomes necessary.

Still another object of the invention resides in the advantages to be obtained in commercial as well as domestic refrigeration by combining the solid carbon dioxide and water ice, by which 25 it is possible to so locate frozen foods in the close vicinity of the solid carbon dioxide and keep them in frozen state without reducing the temperature of the other parts of the refrigerator to such a degree as to be dangerous for preserving 30 other types of food. Moreover, the cost of service is materially reduced since many customers using water ice refrigeration are required to be served with ice daily and the present invention makes it possible to prolong refrigeration so that 35 service may be reduced to the very minimum, which results in a decrease in delivery cost which represents approximately one-third of the retail price of water ice.

With the foregoing and other objects in view, 40 the invention has particular reference to the novel method of associating the refrigerants to bring about the objects set forth and which will become manifest as the description proceeds, and as shown in one form of application in the annexed drawing wherein:

Figure 1 is a longitudinal section view of a railway car, also showing in section the ice bunkers in which the refrigerants are associated.

Figure 2 is a plan view partly in section, showing the ice bunker at one end and the covers at 60 the opposite end.

Figure 3 is a fragmentary view in perspective showing the position of the ice bunker in the end of the car and the means by which the bunkers are filled.

Figure 4 is a perspective view showing the carbon dioxide receptacle.

Continuing more in detail with the drawing, 1 designates the conventional type of railway 70 refrigerating car and showing in Figure 1 the conventional manner in which certain commodities are arranged for shipment.

In practice, bunkers 2 are situated in either 75 end of the car and are filled through openings 3 in the top 4 of the car. These openings are provided with covers 5. When hauling loads of perishable merchandise, care must be taken that the bunkers 2 are filled with water ice so as to insure circulation of cold air throughout the car. Re-icing the bunkers must be done frequently in 80 view of the fact that water ice quickly melts and the refrigerating effects produced thereby accordingly decrease.

This same condition prevails in domestic refrigeration where it is customary in most cases to 85 re-ice the refrigerator daily. With the use of the present invention, re-icing is required only a few times per week, depending of course upon the condition of the ice-refrigerator.

It is a known fact that a large body of water 90 has a tendency to stabilize the climate in its vicinity. This is due to the fact that water has the property of absorbing a large amount of both sensible and latent heat before a change of state 95 takes place. By change of state is meant the changing from a liquid to a solid or from a liquid to a gas. Water likewise has the property of giving off heat when the surrounding air becomes colder than the water. When a sufficient number of B. t. u. of sensible heat are subtracted, the temperature of water will be lowered to 32°. As the water reaches the temperature of 32°, 144 B. t. u. of latent heat must be subtracted before the liquid is turned into a solid (water ice). Likewise in passing from a solid to a liquid, water ice absorbs 144 B. t. u. Water ice has a specific heat of .5 and has the property of absorbing additional heat.

In passing from the solid to the gaseous state 110

at atmospheric pressure, carbon dioxide takes up 248 B. t. u. of heat energy per pound.

The specific heat of solid carbon dioxide at -109° F. is 0.31 B. t. u. per pound per degree F., 5 that is in order to raise or lower the temperature of one pound of solid carbon dioxide one degree F.— at -109° F., 0.31 B. t. u. of heat energy has to be added to or taken from solid carbon dioxide accordingly as its temperature is to be raised or 10 lowered. In the temperature interval between 109° F. and 32° F. the mean specific heat of the vapor is about 0.19 B. t. u. per pound. Therefore 15 one pound of carbon dioxide vapor after subliming from the solid will absorb 0.19 B. t. u. for each degree rise in temperature between 109° F. and 32° F.

Besides the refrigerating effect due to the change of state, there is the additional refrigerating effect of 27 B. t. u. per pound at 32° F. equal to 20 the amount of heat which the carbon dioxide vapor at 109° F. after subliming from the solid, absorbs in being warmed to 32° F. Therefore one 25 pound of carbon dioxide absorbs 275 B. t. u. in changing from a solid at -109° F. to a gas at 32° F. This is approximately equal to twice the 30 amount of heat (144 B. t. u. per pound) absorbed by ice melting at 32° F., and, as this is often expressed, one pound of solid carbon dioxide has approximately the same refrigerating effect at 32° F. as two pounds of water ice.

With special reference to the association of 35 solid carbon dioxide and water ice, from the foregoing it is evident that when solid carbon dioxide is brought into contact with water ice, the water 40 ice will absorb the refrigerating effect produced by the solid carbon dioxide. As long as the ratio of the water ice to solid carbon dioxide is sufficient for the water ice to absorb the refrigerating effect of the solid carbon dioxide, the surrounding air 45 will be affected in temperature by the influence of the water ice only.

Before describing the application of the invention for use in connection with railway refrigeration, certain tests will be defined and the results 50 given, so that a more comprehensive idea of the invention may be had.

The first test embodied the use of a modern 55 type of household refrigerator, having one inch of corkboard and one half inch of wood-tex insulation in the walls and one inch of wood-tex, one inch of balsam wood and one inch of cork-board in the bottom. The capacity of the refrigerator was one hundred pounds. A standard recording thermometer was used for obtaining continuous 60 readings and the accuracy of the thermometer was checked with a standard mercury type thermometer.

The refrigerator was first thoroughly cooled 65 with charging it with one hundred pounds of water ice and air, and allowing it to stand for twenty-four hours. The temperature immediately below the ice compartment was reduced to 42°. The water ice was then removed and five pounds of solid carbon dioxide was supported in the upper 70 part of the ice chamber on a card-board box. The temperature in the milk compartment dropped to 38° in one hour and was maintained at this temperature for another hour and within approximately one and one-half hours longer the 75 temperature had again become 42°. In other words, five pounds of solid carbon dioxide lowered the temperature of the refrigerator for a period of three and one-half hours. The solid carbon dioxide had entirely disappeared in approximately six hours.

A second test was made with 65 pounds of water ice in the ice compartment and five pounds of solid carbon dioxide was wrapped in paper and placed directly on top of the water ice. The temperature in the milk compartment was 44° at the 80 time and in three hours it had dropped to 42° and held this temperature until all of the solid carbon dioxide had been sublimed. There was no appreciable difference in the temperature of the refrigerator with the solid carbon dioxide inserted, but the water ice only melted 12½ pounds during the next 17 hours, whereas with the water ice alone it would have been twenty-five pounds.

In carrying out a third test with the temperature of the refrigerator at 43°, all of the water ice was removed and ten pounds of solid carbon dioxide was inserted, supported on a card-board box in the upper part of the ice chamber. In three hours the temperature dropped to 34° and five hours later the temperature had returned to 43°. The effect of the solid carbon dioxide refrigeration was therefore totally lost in eight hours.

In a fourth test, 50 pounds of water ice was placed in the ice chamber with ten pounds of solid carbon dioxide placed on top of the water ice. The temperature of the refrigerator gradually increased to 44° and the solid carbon dioxide was totally evaporated. During the twenty-five hours following the insertion of the water ice and solid carbon dioxide, only seven pounds of water ice melted.

In addition to the above tests, other tests were conducted with the solid carbon dioxide inclosed in a card-board container and with it thoroughly wrapped in paper, both of which are known to be good heat insulators. The only difference that could be observed was that the rate of sublimation was greatly reduced without there being an appreciable difference in the temperature of the refrigerator. A metal container filled with brine was placed in the ice compartment of the refrigerator. Within the brine solution another metal container was placed, containing five pounds of solid carbon dioxide. A reduction of temperature 110 of the refrigerator was obtained by this method.

The results of the above tests prove conclusively that combinations of solid carbon dioxide and water ice are an improvement in refrigeration. Air is cooled in any refrigerator only by coming 115 in contact with a colder surface. When solid carbon dioxide is placed in contact with the water ice, some of the heat units absorbed by the water ice from the air are transmitted by conduction to the solid carbon dioxide and there absorbed, 120 causing it to sublimate. The air directly in contact with the solid carbon dioxide also causes the carbon dioxide to sublimate. The rate of sublimation is somewhat retarded when the water ice is in contact with the solid carbon dioxide and the surrounding air is not appreciably lower in 125 temperature due to the fact that water ice absorbs a great deal of the refrigerating effect of the solid carbon dioxide. The actual temperature of the air passing over the combination of solid carbon dioxide and water ice is not especially 130 lower than when the solid carbon dioxide is not used. The effect therefore of the combination of solid carbon dioxide and water ice is to increase 135 the life of the water ice without reducing the temperature of the circulating air to a dangerous point. From the tests it is apparent that the best ratio is somewhere near 5 to 1 or one pound of solid carbon dioxide to five pounds of water ice, 140 145 150

although further tests might prove a slight variation in this ratio.

The foregoing explanation, while quite in detail, is intended to present the invention in the most comprehensive manner as applied to both industrial and domestic refrigeration, although the drawing illustrates the mode of application commercially in one form. The association or relationship of the carbon dioxide with the water ice is clearly shown in the drawing and corresponds quite clearly with the description given in the four tests set out in the foregoing.

The refrigerating car which is iced in the customary manner by filling the bunkers 2 with water ice has a funnel-shaped receptacle 6 therein, shown in detail in Figure 4. This receptacle is filled with solid carbon dioxide through the hoppers 7 at either side of the top of the receptacle 6. The hoppers 7 are arranged so that when opened in the manner shown in Figure 4, a chute is provided for convenience in charging the receptacle 6. A gas relief valve 8 is provided for the carbon dioxide receptacle 6 to allow for the escape of sublimating gases.

It has been stated previously that the water ice has a tendency to absorb the effects of the solid carbon dioxide and in so doing, the temperature within the car 1 remains fixed a longer period of time than if water ice alone were used, the solid carbon dioxide preserving the water ice for longer periods of time. The fact that the water ice absorbs the effects of the carbon dioxide prevents the temperature from being lowered to a point where it would be detrimental upon the merchandise within the car.

In order to further lend to the preserving effect of the carbon dioxide upon the water ice, fins 9 are provided on the sides of the receptacle 6.

These fins 9 conduct the frigidity of the carbon dioxide into the bunker 2.

While the invention has been described in great particularity, it is understood that it is not intended that the same shall be limited to the specific details depended upon for the description thereof in the foregoing, and that certain alterations and modifications may be made which may fall within the category of its objects as set forth in the following claims therefor.

What is claimed is:

1. The method of refrigeration which comprises placing a body of carbon dioxide ice adjacent an air space to be refrigerated, placing a body of water ice between said carbon dioxide ice and said space and in thermal contact with said carbon dioxide ice, exposing a surface of the water ice to thermal contact with the air in said space, and proportioning the relative quantities of the two refrigerants so as to prolong the refrigerating effect of said water ice but not to materially reduce the temperature of said exposed surface.

2. In a refrigerator as described, the combination with a refrigerant cabinet, of means for supporting carbon dioxide ice and water ice therein, and heat conducting means interconnecting the two refrigerants, the water ice being in thermal contact with the air currents in the cabinet.

3. The method of cooling a confined space which comprises supporting two solid refrigerants of normally different temperatures within the confined space in heat exchange relation, exposing the refrigerant of higher temperature to thermal contact with the air convection currents in said space and maintaining the refrigerants in heat exchange relation as they change in phase.
